UNITED STATES PATENT OFFICE.

GEORGE E. MOLYNEUX, OF BAYONNE, NEW JERSEY, ASSIGNOR TO THE SINGER
MANUFACTURING COMPANY, A CORPORATION OF NEW JERSEY.

SEWING-MACHINE.

1,111,167.

Specification of Letters Patent. Patented Sept. 22, 1914.

Application filed October 9, 1909. Serial No. 521,801.

To all whom it may concern:

Be it known that I, GEORGE E. MOLYNEUX, a citizen of the United States, residing at Bayonne, in the county of Hudson and State 5 of New Jersey, have invented certain new and useful Improvements in Sewing-Machines, of which the following is a specification, reference being had therein to the accompanying drawings.

- 10 This invention relates to an improvement in that class of sewing machines designed more particularly for stitching seams disposed lengthwise of tubular articles such as the sleeves and legs of garments.
- 15 It has for its object to provide, in conjunction with stitch-forming mechanism comprising a reciprocating needle and a thread-carrying looper, devices for controlling the upper and lower threads in the 20 production of uniform stitching, and to afford means of easy manipulation of the machine in performing its work.

In its preferred form, the improvement is embodied in a machine constructed with 25 a frame comprising a cylinder-bed and an overhanging bracket-arm offset laterally of the cylinder-bed and having a head which is correspondingly offset, so as to bring the needle-bar and presser-bar to one side of 30 the head substantially in the plane of the axis of the cylinder-bed, in order that the work adjacent the stitching position may not be excessively shaded to prevent proper 35 inspection of the work by the operator when the machine is installed in a position imperfectly lighted. The looper is fixed upon a looper-carrier pivotally mounted upon a longitudinal rock-shaft having at its rearward end an operative connection with the 40 main-shaft which extends longitudinally of and is embraced by the cylinder-bed and carries at its forward end a peripherally grooved cam entered by a lateral stud of a reciprocating rod connected with the looper-carrier to which it imparts rocking or 45 needle-avoiding movements. The looper-thread is led through a suitable tension device upon the bracket-arm downwardly through a tubular guide and laterally 50 through the side wall of the cylinder arm whence it passes through the pull-off, nipping and take-up devices and then through an aperture in the opposite side wall of the cylinder-bed from which it extends through 55 an external housing groove in the bed and

enters a longitudinal aperture in the forward end portion of the latter from which it emerges into the looper-inclosing space within the removable end cap of the cylinder-arm. The take-up and pull-off and the intermediate nipper for the looper-thread are actuated by a thread-controller rock-shaft disposed within and transversely of the cylinder-bed beneath its removable cover affording access thereto, this rock-shaft having an adjustable actuating connection with the main-shaft. Upon the thread-controller rock-shaft are mounted for relative circular adjustment the spaced 60 pull-off and take-up thread-engaging cams in the form substantially of triangular arms with rounded outer extremities, these cams being embraced by two pairs of eyed guide-arms pivotally and independently mounted and provided with adjustable stop-screws 65 adapted to engage fixed abutments to adjust the guide-eyes toward and from the axis of oscillation of their respective thread-engaging cams. Fixed upon the thread-controller rock-shaft intermediate its take-up 70 and pull-off cams is a nipper-actuating cam adapted to act upon a nipper-lever carrying one jaw of the nipper disposed intermediate the two pairs of guide-arms, the other jaw of which is fixed with its operative 75 face in substantial alinement with the thread-eyes of said guide-arms.

In the accompanying drawings, Figure 1 is a rear side elevation, and Fig. 2 a sectional front side elevation, representing a feed-up-the-arm sewing machine embodying the present improvements. Fig. 3 is a rear end elevation of the machine with the base and hollow standard of the bracket-arm in section to expose the parts inclosed therein, and 90 Fig. 4 is a front end view of the machine with the forward end of the work-supporting arm or horn in section and the face-plate removed. Fig. 5 is a plan of the machine with the base of the bracket-arm in section 95 and the overhanging member of the same removed and the cover-plates for the work-support omitted. Fig. 6 is a transverse section of the outer end portion of the cylinder bed, and Fig. 7 a perspective view of 100 the removable end cap of the same. Fig. 8 is a perspective view of the looper-carrier and looper, and Fig. 9 a similar view of the looper-carrier supporting stud. Fig. 10 is a detail side view of the looper-carrier rock- 105

110

ing mechanism, and Fig. 11 a perspective view of a member of the connection between such mechanism and the looper-carrier. Fig. 12 is a perspective view of the upper portion of the head of the bracket-arm with its needle-thread controlling mechanism. Fig. 13 is a perspective view of the looper-thread controlling mechanism. Fig. 14 is an enlarged detail sectional plan view representing one side of the work-supporting horn with the thread-housing groove therein. Fig. 15 is a sectional elevation of one of the needle-thread tension devices, and Figs. 16, 17 and 18 are detail views of portions of the feed-actuating mechanism.

The frame of the machine is shown formed with the hollow base 1 and standard 1*, overhanging bracket-arm 2 and cylinder bed or work-supporting horn 3 having its flange 4 secured by screws 5 to the base beneath the bracket-arm. As represented particularly in end view in Figs. 3 and 4, the bracket-arm is offset from the hollow standard of the frame backwardly toward the rear side 25 of the machine in relation to the center of the cylinder bed which latter it does not thus overhang at the front side; the head 6 of the bracket-arm being similarly offset to such extent that, while its front side is 30 directly above the corresponding side of the bed, the rearward side extends materially backwardly of the rear of the bed, and is substantially flush with the back of the arm 2 and upper portion of the frame standard, 35 as indicated in face view in Fig. 1. The standard is provided at the rear end with a bearing boss 7 containing the bushing 8 in which is journaled the rear end of the main-shaft 9 fitted within a bearing member 10 formed upon the rearward end of the work-supporting arm 3. The reduced forward portion 9* of the main-shaft is journaled in a bearing boss 11 near the forward end of the arm 3. The bracket-arm is provided at 40 its rearward end with a bearing boss 12 in which is journaled the rearward end of the needle-actuating rock-shaft 13 whose forward end is fitted to and passes through the bearing member 14 into the cavity 6* in 45 the head 6 of the bracket-arm, where it is provided with the usual crank-arm 15 carrying a pin 16 connected by means of the pitman 17 with a lateral pin upon the collar 18 fixed upon the needle-bar 19 carrying 50 the spaced eye-pointed needles 20. Upon the rearward end of the rock-shaft 13 is fixed the lateral crank-arm 21 which carries the stud 22 embraced by the upper end of a pitman 23 whose lower end embraces a 55 crank 24 formed in the main-shaft 9 and adapted to communicate through the described connecting mechanism reciprocating movements to the needle-bar and needle.

The needle-actuating rock-shaft 13 has 60 fixed thereon, at the opposite side of the

bearing boss 12 from the crank-arm 21, a second lateral crank-arm 25 carrying a screw-stud 26 embraced by the upper end of the pitman rod 27 whose lower end embraces a screw-stud 28 intermediate the 70 ends of a vibrating lever 29 having one end journaled upon the fixed fulcrum-pin 30 mounted in an inwardly projecting boss 31 formed upon the standard 1. The outer end of the lever 29 carries a screw-pin 32 75 connected by means of a link 33 with a similar pin 34 carried by a crank-arm 35 fixed upon the rearward end of the looper rock-shaft 36. The component members of the operative connections between the needle-actuating and looper rock-shafts are so arranged and proportioned that the rocking of the former through its crank and pitman connections with the actuating crank 24 of the main-shaft causes the screw-pin 80 32 to move into and out of alignment with the fulcrum-pin 30 and crank-pin 34 of the crank-arm 35 in imparting each complete reciprocation of the needle, whereby the looper rock-shaft receives a dwell in the production of each stitch as the needles attain their highest position and begin their descent for a succeeding stitch.

The looper-shaft 36 is journaled at its rearward end in the bearing member 10 and 95 at its forward end in the bearing member 37 within the cylinder-bed 3 and parallel with the main-shaft, and has secured adjustably, both longitudinally and circularly, upon its forward end, by means of clamping screws 38, the split collar 39 with forwardly projecting stud 40 of angular cross-section with parallel sides, as shown particularly in Fig. 9. The stud 40 is provided with a transverse aperture 41 and the axial screw-hole 42 extending from its forward extremity. The looper-carrier 43 is formed at its upper end with the usual socket in which is secured by means of the fastening screw 44 the shank of the eyed-looper 45 whose blade 46 is arranged in practice transversely of the cylinder-bed and the supporting shaft 36. The body of the looper-carrier is formed with a rectangular transverse aperture 47 whose parallel opposite sides are 100 fitted to the perforated sides of the supporting stud 40 upon which it is pivotally mounted by means of the fulcrum-pin 48 having the flat side 49 engaged by the point of the stud-screw 50 entering the axial screw-hole 42 of the supporting stud. In its lower end, the looper-carrier is split and formed with a segmental raceway 51 whose walls are relatively adjustable by means of the transverse adjusting screws 52 crossing the slotted portion of the body of the looper-carrier. As thus mounted, the looper derives its operative loop-seizing and shedding movements from its supporting rock-shaft 105 53, and its sidewise or needle-avoiding move- 110

ments are imparted to it by means of an actuating cam 53 secured upon the forward end of the main-shaft extension 9* by means of set-screws 54, and provided with a peripheral cam-groove 55.

Journaled in the bearing member 37 beneath and parallel with the looper rock-shaft 36 is a reciprocating rod 56 formed upon one side with a spline 57 to prevent its turning while permitting its free endwise movement, and having adjustably secured to its rearward end by means of set-screws 58 a collar 59 with a rearwardly extending arm 60 carrying a roller-stud 61 entering the groove 55 of the cam 53 from which it derives its reciprocatory movements. The reduced forward end portion 62 of the rod 56 is vertically split and provided with a socket in which is fitted and in which may be secured by means of the clamp-screw 62* the shank 63 of a ball-stud whose spherical portion 64 is fitted within the suitably socketed independent sections 65 of a wearing block which is in turn fitted within the segmental raceway 51 of the looper-carrier whereby the looper-carrier is permitted to oscillate freely with its supporting shaft, while the reciprocating movements of the rod 56 are communicated through the stud 63 64 and slide-block 65 to the looper-carrier which is thereby caused to rock upon the fulcrum-pin 48. By reference to Fig. 11 it will be observed that the adjacent faces of the slide-block sections 65 are slightly separated, owing to portions of their sockets being slightly shallower than the diameter of the ball 64 upon which they are fitted. The adjusting screws 52 of the looper-carrier therefore not only take up the wear of the slide-block sections 65 upon the side walls of the raceway, but serve to close the slide-block sections upon the ball-stud to compensate for the wear of the latter in its socket.

45 As will be observed by reference more particularly to Figs. 2 and 6, the bearing members 11 and 37, of the cam-cylinder are so arranged as to afford an intermediate oil cavity 66 in which the cam-cylinder 53 is inclosed, whereby the same is effectively lubricated at all times.

The machine is shown provided with the power transmitting device forming the subject of my Patent No. 987,640, of March 21, 55 1911, whereby means are provided for automatically connecting with the main-shaft a transverse hand-wheel shaft 67 provided in a bushing 68 in a lateral bearing boss 69 of the base 1 and carrying the hand-wheel 70. To this end, the shaft 67 carries a bevel 60 friction-wheel 71 normally in contact relation with a similar bevel-wheel 72 slidably mounted upon the main-shaft 9 and provided with a hub 73 having an annular 65 groove 74. The hub of the wheel 72 is

splined upon the shaft 9 so as to rotate therewith while being freely movable endwise thereon.

Fixed upon the shaft 9 adjacent the hub 73 is a spider comprising the collar 75 with 70 forwardly and outwardly projecting arms 76 each forked in its outer end to embrace a bell-crank lever comprising the arm 77 provided with a spherical weight 78 and pivoted to said arm by means of a pin 79. The 75 other angularly arranged arm of the bell-crank lever terminates in a ball 80 entering the groove 74 in the hub 73 of the wheel 72.

A spring 81 interposed between the fixed collar 75 and the sliding hub 73 serves to 80 maintain the wheel 72 in operative contact relation with the wheel 71 when the machine is at rest, but as soon as the machine attains sufficient speed, the weights 78 fly out by centrifugal action, thus shifting the bell-crank levers 77, 80, and retracting the wheel 72 from contact with the wheel 71. The hand-wheel 70 is thereby permitted to come to rest and to remain inactive while the stitching proceeds. As the machine is 90 stopped the spring 81 overcomes the reduced centrifugal action of the weighted bell-crank levers and operates to recouple the friction wheels 72 and 71 for the customary manual control at the beginning and 95 end of a stitching operation. As the cross-shaft 67 carrying the comparatively heavy balance-wheel 70 becomes disconnected from the main-shaft soon after the latter begins to rotate, the load upon the main-shaft during the greater part of each continuous stitching operation is only that of the active parts of the mechanism without the usual dead weight, and consequently the machine attains full speed much sooner than when it 100 has the additional load imposed by the inertia of the balance-wheel. For a corresponding reason, the automatic recoupling of the balance-wheel shaft with the main-shaft as the machine is coming to rest causes 105 the braking of the machine incurred by the added load imposed in overcoming the inertia of the balance-wheel shaft with its load.

The friction-wheel 72 is shown formed of 110 a body portion of yielding material, such as leather, clamped between two disks 82 and 83, the forward disk being formed with an annular recess 84 in which is pivoted by means of a shouldered screw 85 a lateral ear 120 or flange 86 of the ball-eccentric 87 which is provided with an oppositely extending lateral ear or flange 88 in which is tapped the threaded forward extremity of an adjusting screw 89 passing through a segmental slot 125 90 formed concentric with the screw 85 and extending through the wheel 72, the head of the screw 89 being normally seated upon the back of the disk 82. In order to permit the lateral shifting of the eccentric 87, it is 130

formed with a slot 91 which is also concentric with the pivotal screw 85, the lateral movement of the eccentric in relation to the main-shaft providing for the adjustment of its throw in a manner well-known.

- 5 The feed eccentric 87 is embraced by the strap 92 of an eccentric rod 93 whose opposite end embraces a ball-eccentric upon the rearwardly extending arm 94 of a plural-
 10 armed rocker mounted upon the fixed fulcrum-stud 95 carried by the lug 96 extending inwardly from the wall of the base 1, and having a second laterally extending arm 97 carrying a ball-stud embraced by a strap
 15 98 at the rearward end of the feed-bar 99 extending longitudinally through the work-supporting arm 3 above the rock-shaft 36 and formed near its forward end with a reduced cylindrical portion 100 to which is se-
 20 cured the slide-block 101 channelled in its upper side to receive the shank 102 of the serrated feed-dog 103 secured therein by means of the fastening screw 104. The bearing member 37 of the arm 3 is notched in
 25 its upper side in a manner well-known to form a longitudinal guideway for the slide-block 101.

To the reduced intermediate portion 100 of the feed-bar 89 is slidably fitted a tilting bearing or fulcrum-block 105 formed with lateral bosses 106 which are entered by the fulcrum-screws 107 passing through the opposite members of a yoke 108 embracing said block and formed at the upper end of an up-
 30 right lifting bar or post 109 apertured at its lower end to form a strap 109^x to embrace the feed-lifting eccentric 110 fixed upon the reduced forward portion 9^x of the main-shaft 9 adjacent the cam-cylinder 53 and dis-
 35 posed within the oil cavity 66. The post 109 has also a clearance aperture intermediate its ends through which passes looper rock-shaft 36.

As will be observed, the longitudinal re-
 45 ciprocating movement of the feed-bar for effecting the advance of the work up the arm of the machine toward the standard 1^x is produced through its described connections with the feed-actuating eccentric 87, while
 50 the rising and falling movements of the feed-dog are produced by the feed-lifting eccentric 110 through the post 109 and tilting bearing 105 swiveled therein.

It will be observed that, by extending the
 55 driving shaft 9 into the forward end of the work-supporting arm 3, not only is it practicable to impart the lifting movements to the feed-bar directly therefrom adjacent the point of engagement of the feed-dog with
 60 the work, but the rocking movements of the looper-carrier may be communicated by the employment of a short rod or pin 56 of light weight and therefore offering little momentum to overcome in the operation of the ma-
 65 chine at high speeds. By the employment

of a grooved cam, the pin 56 is adapted to be disposed in alinement with the shaft section 9^x, the parts being thus arranged very compactly, so as to provide for a work-supporting arm 3 of small diameter for accommodation of hollow articles of the smallest sizes, such as sleeves of childrens' garments, which the machine is designed to stitch.

Journaled upon center-screws 111 extending inwardly through the walls of the upper portion of the arm 3 is the transverse thread-controller rock-shaft 112 having fixed thereon the upwardly extending take-up cam-arm 113 with cam-shaped hub 114 and adjacent pull-off cam-arm 115 whose hub 116 is secured for circular adjustment upon the shaft 112 by means of the set-screw 117. The cam-arms 113 and 115 are of substantially triangular shape with rounded outer ends, and each is embraced by a pair of guide-arms 118 119 and 120 121, respectively, the arms of each pair being formed upon a plate 122 123, respectively, each of which plates is formed with a rearwardly extending lug 124 pivotally mounted by means of the fulcrum-pin 125 upon the reduced upper end portion 126 of the stand 127 whose foot 128 is formed with a longitudinal tongue 129 and fitted upon the top of a lug 130 rising from the bottom of the horn 3 upon which it is secured by means of the screw 131. Each of the plates 122 and 123 is provided with a stop-screw 132 passing through the same and resting upon a shoulder afforded by the upper portion of the stand 127, and by turning either of these stop-screws the normal position of the arms carried by the respective plates is adjusted relatively to the outer or operative portions of the cam-arms. Each of the several guide-arms is provided with a thread-eye 133 adapted to be disposed in alinement with those of the other arms in certain positions of the latter.

The stand 127 carries an upwardly extending lug 134 whose flat forward face is disposed directly above the nipper-actuating cam 114 afforded by the hub of the take-up cam 113, and opposed to the fixed nipper-jaw thus provided is a spring-jaw 135 afforded by the flat spring 136 extending upwardly from the foot 128 of the stand 127 upon which it is rigidly secured by means of the screw 137.

For convenience in lifting the thread arms for threading, the arms 119 120 are extended forwardly and toward each other beyond their respective thread-eyes, and either may be engaged by the finger of the operator for lifting the pair forming a part of either the take-up or pull-off device. As will be observed, the thread-eyes of the guide-arms are all arranged at the same distance from the fulcrum-pin 125 as the operative face of the fixed nipper-jaw 134, so that when the nipper-jaw is opened while the

take-up and pull-off cams are in their extreme forward or backward positions, the thread is permitted to pass freely in a straight line through the apertured guide-
5 arms and between the nipper-jaws.

Fixed adjustably upon the thread-controller shaft 112 by means of the set-screw 138 is a crank-arm 139 pivotally connected by means of the stud-screw 140 with one end 10 of a pitman-rod 141 whose opposite end is pivotally connected by means of a pin 142 with an upwardly extending arm 143 of a rock-shaft 144 provided with a lateral arm 145 carrying a ball-stud 146 embraced by 15 one end of an eccentric-rod 147 having at its opposite end a strap which embraces the ball-eccentric 148 fixed upon the main-shaft adjacent the needle-actuating crank 24. Through the connections above described, 20 the eccentric 148 imparts rocking movements to the thread-controller shaft 112. By circularly adjusting the position of the crank-arm 139 upon the rock-shaft 112 the looper-thread engaging members controlled thereby 25 may be set forwardly or backwardly to change the time of their action in setting the stitch and drawing thread for a succeeding stitch; and by adjusting the cam-arm 115 upon such shaft by loosening and re- 30 tightening the set-screw 117, the relation of the pull-off cam to the take-up and nipper-actuating cams may be changed. It will thus be seen that the take-up and pull-off cams are adjustable in unison or relatively to produce the desired timing for 35 properly handling different kinds of thread in the performance of different kinds of work.

Cooperating with the feed-dog 103 in controlling the feed of the work is the presser-foot 149 whose shank 150 is rigidly secured to the lower end of the presser-bar 151 journaled in suitable bearings in the head 6 of the bracket-arm in the plane of the needle-bar 40 in relation to the direction of feed and the center of the work-supporting horn. The cavity 6^x of the head 6 is provided with a rearwardly extending aperture 152 through which passes a lateral lug 153 of a 45 collar 154 fixed upon the presser-bar 151; the top of the lug 153 affording a seat for the free end of a flat pressure spring 155 secured by means of a pin 156 upon a lug 157 extending from the standard 1^x and being engaged intermediate its ends by the 50 depending knurled head 158 of an adjusting screw 159 tapped into a boss 160 in the lower side of the bracket-arm 2 and maintained against working loose by means of 55 the set-nut 161. A finger-lever 162 with cam-shaped operative end 163 is pivotally mounted in the head 6 and adapted to engage the under side of the lug 153 for lifting 60 the presser-foot by hand. The presser-bar 65 is provided above the collar 154 with a sec-

ond collar 164 provided with a rigid lateral arm 165 to which is pivotally connected the lower end of the rod 166 whose upper end is pivotally attached to one end of a rock-lever 167 fulcrumed intermediate its ends 70 by means of a screw 168 upon a stud 169 secured for vertical adjustment in a suitable socket in the head 6 of the bracket-arm by means of the set-screw 170. The opposite end of the rock-lever is formed with a trans- 75 verse guide-slot 171 crossed by an arm 172 adjustably secured upon the rock-lever 167 by means of a clamp-screw 173. As will be observed, the rock-lever 167 is normally stationary, but is tilted more or less upon its 80 fulcrum-pin 168 by the rise and fall of the presser-foot under variations in the thickness of the material operated upon.

The upper end of the needle-bar is provided with a washer 174 from which projects laterally a finger 175 provided with suitable upper thread-guiding eyes, and in advance of the said eyes and in line with the slotted end of the rock-lever 167 is disposed the fixed upwardly extending thread-guiding arm 176 having in its upper extremity the guide-eyes 177, the shank 178 of said arm being let into a seat formed in the forward face of the head 6 of the bracket-arm and secured therein for vertical adjustment 90 by means of the fastening screw 179 passing through a slot 180 therein.

Mounted upon a fulcrum-stud 181 upon the rearward side of the arm 2 is a presser-foot lifting lever 182 whose forward portion enters a vertical slot 183 in the rear side of the head 6 of the bracket-arm within which it is turned upwardly to form a crook extending beneath the arm 165 of the collar 164, and provided with a lug 184 between 105 which and a staple 185 upon the bottom of the cavity 6^x is a spring 186 for maintaining the forward arm of the lifter-lever depressed out of contact with the arm 165 rigidly connected with the presser-bar. The 110 rearwardly extending arm 182^x of the lifter-lever has an eye at its rearward end to which is applied the hooked upper end of a buffer spring 187 to which is connected the treadle or knee-lever chain 188 by which the 115 lifter-lever is tilted to raise the presser-foot and draw off an extra length of the needle-thread passing through the eye 171 of the rock-lever 167 for beginning a succeeding stitching operation.

Secured upon the top of the bracket-arm by means of the fastening screw 189 is a bracket 190 into which are tapped the shoudered tubular posts 191 of the needle-thread tension devices each provided in the upper 125 portion with a vertical diametrical slit 192 and threaded externally to receive the nut 193 between which and the washer 194 resting upon the upper member of a pair of tension-disks 195 is interposed the spring 196. 130

Clamped upon the bracket 190 by means of the posts 191 are the plates 197 each provided with a perforated guide-ear 198 for directing the thread between the respective tension-disks. The washer 194 is provided with the usual perforation for passage of the post 191 and with a cross-bar 194^x extending through the slit 192, and within the axial aperture of each post 191 is loosely fitted the thrust-pin 199 whose upper end bears upon the cross-bar 194^x of the washer 194 and whose lower end rests upon one of two cams or eccentrics 200 upon a transverse rock-shaft 201 journaled in the bracket 190. Upon the rearward end of the shaft 201 is adjustably secured by means of a setscrew 202 the hub of a crank-arm 203 which is pivotally connected with the upper end of a link 204 having its lower end pivotally attached to the rearward arm 182^x of the presser-foot lifter lever. As will be observed, when the lifter-lever is operated at the end of a stitching operation to lift the presser-foot clear of the work, the pressure of the tension springs 196 may be entirely removed from the tension-disks 195, so that the needle-thread may be freely drawn through the tension device by the actuation of the rock-lever 167 in drawing off thread for the succeeding stitching operation.

The tension device for the lower thread is arranged upon the front side of the arm 2 near the standard 1^x, and is or may be similar to the tension devices for the needle-threads, excepting that no release is provided therefor. This tension device comprises the tension disks 205 normally pressed together by means of the spring 206 interposed between one member of the same and the nut 207 upon the threaded post 208, the thread being led to the machine through an aperture in the guide-ear 209 upon the disk 210. The looper-thread, after passing between the tension-disks 205 enters the upper end of the standing guide-tube 211, provided with a series of lateral apertures 212 for purposes of inspection, and formed at the lower end with an angularly arranged nipple 213 entering an aperture through the wall of the rearward end portion of the cylinder-arm 3, a notch 214 being formed at the junction of the nipple with the lower end of the guide-tube 211 to facilitate threading. After passing through the pull-off, nipping and take-up devices as before explained, the looper-thread enters, through the threading slit 215^x, a transverse aperture 215 in the rear wall of the cylinder-bed from which it is led along the bottom of an external longitudinal housing groove 216 formed in the bed to a second transverse aperture 217 leading into a longitudinal aperture 218 passing through the bearing member 37 at the rearward side of the feed-bar slide-block 101. As the thread emerges

from the lower end of the aperture 218 it is threaded through the eyes of the looper-blade in a well-known manner.

The forward end of the body of the horn 3 is formed with a reduced or shouldered portion 219 upon which is fitted the adjacent extremity of the removable end-cap 220 which effectively closes the extension-slit 216^x continuing to the forward extremity of the member 37 the lateral thread passage leading from the aperture 215, this extension being provided for convenience in threading the machine.

Upon the front of the bed is secured by means of screws 221 the throat-plate 222 provided with the usual feed-dog openings 223 and needle-holes 224, and at the opposite end, which is slightly flared toward the base 1, is disposed an arched cover-plate 225 provided with spaced perforated lugs 226 entered by the pin 227 by which it is hinged to a lug 228 upon the front side of the flange 4, this cover normally closing the otherwise open top of the horn 3 above the lower-thread controlling devices, but being removable to afford access thereto for threading and other purposes.

The top of the horn 3 is closed intermediate the removable cover-plate or cover 225 and the throat-plate 222 by means of the plate 229 secured thereon by fastening screws 230.

The rearward end of the main-shaft is provided with the usual grooved belt-wheel 231 embraced by a belt from the source of power and confined thereon from accidental displacement by means of the guard-post 232 extending rearwardly from the back of the base 1.

In threading the machine, the needle-threads *a* and looper-thread *b* are led through their several tensions and thread-controlling devices to the needles and looper, respectively, as before indicated, and as represented in Figs. 2, 5, 12 and 14 of the drawings. As will be observed, the needle-thread engaging members 171 and 177 are so positioned that the finger 175 moves first above and then below the same, whereby each stroke of the needle-bar while the tensions are in normally closed position causes an initial slackening and a subsequent pull upon the needle-thread. The parts are so timed that the needle-threads are slackened as the needles begin to descend until their eyes have descended beneath the work, but are thereafter drawn up; and the preceding stitches are finally set as the needles reach their lowest position, the lower-thread nipple being open at this time so as to permit the lower-thread loop to be readily drawn into place beneath the fabric. As the needles begin to rise to present their loops to the looper, the needle-threads are again slackened while their loops are entered by the

looper, but as the needle-bar reaches its highest position, the needle-threads are tightened so as to draw through the tension devices 195 sufficient needle-thread for the 5 succeeding stitch formation. As regards the handling of the lower thread, when the needles assume their extreme upper positions, the lower-thread take-up and pull-off cam-arms are in extreme retracted position 10 and the intermediate nipper open, the looper being in the extreme advance position with needle-thread loops upon its blade, the needle-avoiding motion of the looper having just been completed simultaneously with 15 the feeding action for advancing the work. As the needles descend with their points about to enter the throat-plate, the looper-thread take-up and pull-off arms advance slightly past their central position opposite 20 the thread-eyes of the embracing guide-arms and the nipper closes upon the thread prior to the arrival of the take-up and pull-off arms at cast-off position, the looper at this stage beginning its retrograde or loop-shed. 25 ding movement, and its thread being maintained taut by the final take-up action of the cam-arm 113 until the points of the needles descend below the looper-thread intermediate the needle-hole of the throat-plate and the 30 eye in the looper point. While the needles are descending to extreme lower position, the looper continues its retrogressive movement until its point is beyond the farthest needle, when the quick sidewise or needle-avoiding 35 movement takes place so as to bring the lead of the looper-thread from the looper-point directly to the needle-hole, when the arrival of the needles to their extreme lower position effects the setting of the stitch and the 40 drawing of sufficient looper-thread for the purpose freely through the looper from the supply previously drawn through the tension and through the now open nipper. As the needles begin to rise, the looper commences 45 its advance or loop-seizing movement, the nipper closing simultaneously and the receding take-up consequently drawing up slack looper-thread, while the pull-off at the same time draws a fresh supply of 50 looper-thread through the tension, this action continuing until the looper enters the thread-loops presented by the needles, when the take-up and pull-off arrive at cast-off position and the nipper opens. As the 55 looper continues to advance, it draws the slack just supplied by the pull-off and moves into extreme advance position, the needles arriving at the extreme upper position at the same time preparatory to the performance 60 of a succeeding stitch-forming cycle.

In machines of this general character as heretofore constructed, it has been found necessary for the operator to grasp the needle-threads intermediate the tension device and the needle-bar to draw off a suffi-

cient thread supply to permit the withdrawal of the work for the succeeding stitching operation without endangering the unthreading of the needles. According to the present invention, the tensions are released 70 simultaneously with the lifting of the presser-foot for the removal of the work, thus leaving the needle-threads entirely free to be drawn through the needles in the removal of the work, and leaving the hands 75 of the operator entirely free for the handling of the work.

From the foregoing description, it will be seen that the present improvement includes various constructive features of a 80 novel character all of which contribute to the efficiency and convenience of operation of the machine, and that these several features are susceptible of considerable modification in construction and arrangement of 85 their constituent parts without departing from the present invention.

Having thus set forth the nature of the invention, what I claim herein is:—

1. In a sewing machine, the combination 90 with the frame comprising a hollow standard sustaining a laterally closed work-supporting horn and an overhanging bracket-arm, and a main-shaft journaled in said frame, of a reciprocating needle and means 95 connected with the main-shaft for actuating it, a looper coöperating with said needle and disposed within the work-supporting horn, means connected with the main-shaft for imparting operative loop-seizing movements 100 to said looper, a thread-controller rock-shaft independent of the looper-actuating mechanism and mounted within said work-supporting horn, means connected with the main-shaft within said standard and independently of its connections with the needle and loop-taker for actuating said rock-shaft, thread-controlling means carried by 105 said rock-shaft for acting upon the looper-thread, and means applied to said work-supporting arm for affording access to the thread-controlling means.

2. In a sewing machine, the combination 110 with the frame comprising a laterally closed work-supporting horn and an overhanging bracket-arm, and a main-shaft journaled within and disposed longitudinally of the work-supporting horn, of a reciprocating needle and means connected with the main-shaft for actuating it, a looper coöperating 115 with said needle and disposed within the work-supporting horn, means connected with the main-shaft for imparting operative loop-seizing movements to said looper, a thread-controller rock-shaft disposed 120 within and in transverse relation to the work-supporting horn, means connected with the main-shaft independently of its connections with the needle and the looper for actuating said rock-shaft, thread-controlling 125 130

- means carried by said rock-shaft for acting upon the looper-thread, and means applied to said work-supporting arm for affording access to the thread-controlling means.
3. In a sewing machine, the combination with stitch-forming mechanism including a reciprocating needle, a coöperating eyed looper, and a looper-supporting shaft, of a rock-shaft, means for actuating said rock-shaft movable differentially of the looper-supporting shaft, a take-up cam-arm extending from one side of said rock-shaft and formed with thread-engaging opposite edges and an intermediate cast-off portion upon the outer extremity, both of said thread-engaging edges being substantially eccentric to said rock-shaft, and thread-guiding eyes disposed upon opposite sides of the path of movement of said take-up cam-arm.
4. In a sewing machine, the combination with stitch-forming mechanism including a reciprocating needle and a coöperating eyed looper, of a rock-shaft, means for actuating said rock-shaft, take-up and pull-off cams with an intermediate thread-nipper actuating cam mounted upon said rock-shaft, said cam-arms being extended each from one side of said rock-shaft and formed with thread-engaging opposite edges and an intermediate cast-off portion upon the outer extremity, a thread-nipper substantially intermediate the take-up and pull-off cam-arms and one of whose thread-engaging jaws is operated by said actuating cam, and a plurality of guide-arms embracing said take-up and pull-off cam-arms and thread-nipper and provided with thread-eyes adapted for disposition in substantial alinement.
5. In a sewing machine, the combination with stitch-forming mechanism including a reciprocating needle and a coöperating eyed looper, of a rock-shaft, means for actuating said rock-shaft, take-up and pull-off cams mounted upon and adapted for relative circular adjustment upon said rock-shaft, an intermediate thread-nipper actuating cam also mounted upon said rock-shaft, a thread-nipper substantially intermediate the take-up and pull-off cams and one of whose thread-engaging jaws is operated by said actuating cam, and a plurality of guide-arms embracing said take-up and pull-off cams and thread-nipper and provided with thread-eyes adapted for disposition in substantial alinement.
6. In a sewing machine, the combination with the frame comprising a cylindrical work-supporting horn and an overhanging bracket-arm, and stitch-forming mechanism including a reciprocating needle and a coöperating eyed looper, of a rock-shaft disposed within said work-supporting horn, spaced take-up and pull-off cam-arms with an intermediate thread-nipper actuating cam fixed upon said rock-shaft, a thread-nipper intermediate the take-up and pull-off cam-arms and having one of its thread-engaging jaws in operative relation with said actuating cam, a plurality of guide-arms provided with thread-eyes and embracing said take-up and pull-off cam-arms and the thread-nipper, and means for actuating said rock-shaft to move said cam-arms repeatedly into and out of alinement with the thread-eyes of their respective guide-arms in each stitch-forming cycle.
7. In a sewing machine, the combination with stitch-forming mechanism including a reciprocating needle and a coöperating eyed looper, of a rock-shaft, means for actuating said rock-shaft, take-up and pull-off cams with an intermediate thread-nipper actuating cam mounted upon said rock-shaft, a thread-nipper substantially intermediate the take-up and pull-off cams and one of whose thread-engaging jaws is operated by said actuating cam, two pairs of independently movable guide-arms embracing respectively the take-up cam and the pull-off cam, and embracing between them the thread-nipper, thread-eyes within said guide-arms adapted to be arranged in alinement, and means for independently adjusting the positions of said pairs of guide-arms.
8. In a sewing machine, the combination with the frame comprising a work-supporting horn substantially closed at its outer end and provided in its opposite end portion with a removable cover for access to its interior, and a removable cap applied to the forward end of said work-supporting horn and confining a space at the end of the latter, of stitch-forming mechanism comprising a reciprocating needle and an eyed looper mounted within and embraced by said cap at the end of the work-supporting horn, means for actuating said needle and looper, a looper-thread controlling device arranged within the work-supporting horn and beneath its removable cover, and means for actuating it, the work-supporting horn being provided with an external longitudinally extending thread-housing groove open throughout its length at the periphery of the horn to admit the looper-thread laterally therein and connected at one end by a transverse aperture with the interior adjacent the looper-thread controlling device and at the other end with an aperture through the forward portion of the horn with the space surrounding the looper inclosed by said removable cap.
9. In a sewing machine, the combination with the frame comprising a standard from which extends a laterally closed work-supporting horn with a top closed at its outer end portion but formed with an opening adjacent the standard, and an overhanging bracket-arm, of stitch-forming mechanism including an eyed looper disposed within

9

said horn, feeding mechanism with actuating means therefor to impart to the same longitudinal work - advancing movements along said horn toward the standard, a 5 looper-thread take-up movable upon an axis transverse to said horn and disposed within and beneath the said opening therein, and a hinged cover for said opening in the horn adapted to be withdrawn for access to the 10 take-up device.

10. In a sewing machine, the combination with the frame comprising a laterally closed work-supporting horn and an overhanging bracket-arm, and a main-shaft journaled in 15 said frame, of a reciprocating needle and actuating means therefor, a looper coöoperating with said needle and disposed within the work - supporting horn, looper - actuating

means connected to the main-shaft externally to and at one end of the work-supporting horn for imparting to the looper its loop-seizing movements, a rocking thread-controller acting upon the looper-thread and disposed within the work-supporting horn, and an operative connection between the 20 25 thread-controller and the main-shaft independent of the connection of the looper-actuating means with the main-shaft and also external to but at the end of the horn.

In testimony whereof, I have signed my 30 name to this specification, in the presence of two subscribing witnesses.

GEORGE E. MOLYNEUX.
